[57] CLAIM

The ornamental design of a plastic canvas holding rack for needlepointing, as shown and described.

DESCRIPTION

FIG. 1 is a bottom plan view of a plastic canvas holding rack for needlepointing showing my new design;

FIG. 2 is a top plan view thereof, with one slide shown in an upright position;

FIG. 3 is a front elevational view, with the rear elevational view being a mirror image thereof;

FIG. 4 is a right side elevational view, with the left side elevational view being a mirror image thereof; and,

FIG. 5 is a top front perspective view, with both slides shown in an upright position and the clip handle rotated 90 degrees.
